UNITED STATES PATENT OFFICE.

JACOB GORDON, OF BROOKLYN, NEW YORK.

DESIGN FOR A TOY BALLOON.

Application filed May 13, 1927. Serial No. 21,953. Term of patent 7 years.

To all whom it may concern:

Be it known that I, JACOB GORDON, a citizen of the United States of America, residing in the borough of Brooklyn, county of Kings, city and State of New York, have invented a new, original, and ornamental Design for Toy Balloons, of which the following is a specification, reference being had to the accompanying drawing, forming a part thereof, in which:

The figure is a perspective view of a toy balloon illustrating my new design.

I claim:

The ornamental design for a toy balloon, substantially as shown.

This specification signed this 10th day of May, 1927.

JACOB GORDON.
